UNITED STATES PATENT OFFICE.

LAFE SWANK, OF ANDERSON, INDIANA.

DESIGN FOR A WIRE FENCE.

No. 39,861.

Specification for Design.

Patented March 2, 1909.

Application filed December 14, 1907. Serial No. 406,571. Term of patent 14 years.

To all whom it may concern:

Be it known that I, LAFE SWANK, a citizen of the United States, residing at Anderson, in the county of Madison and State of Indiana, have invented a new, original, and ornamental Design for a Wire Fence, of which the following is a specification.

The accompanying figure of drawing is an elevation of a portion of a fence showing my new design.

The design comprises a plurality of pairs of U-shaped pickets, the pickets of each pair overlapping each other substantially half of

the width of the U and the adjacent pickets of adjacent pairs being separated. The several pairs of pickets are embodied in the fence structure by means of two or more longitudinal members connected to said U-shaped pickets.

I claim:

The ornamental design for a wire fence, as shown and described.

LAFE SWANK. [L. S.]
